corporation of Illinois

Application November 16, 1939, Serial No. 304,677

4 Claims. (Cl. 126—110)

This invention relates generally to furnaces and has particular reference to a furnace which is arranged to positively circulate and filter the air being heated.

It is an object of this invention to provide a furnace in which the novel arrangement of the parts of the furnace provide for an efficient and compactly arranged furnace so that the overall dimensions are relatively small.

It is another object of this invention to provide a furnace which may be prefabricated in sections so that very little work is required in the field to assemble the furnace.

It is another object of this invention to provide heat exchange surfaces within a furnace in such a manner as to make use of practically all the heat generated by the burner.

It is another object of this invention to provide a furnace in which the draft within the combustion chamber is maintained at a relatively constant figure by means of a suction blower in the exhaust passage to the chimney.

It is another object of this invention to provide a furnace in which power for the process of combustion and power for circulating the air being heated is provided by a single motor.

Other objects and advantages of this invention will be apparent from a consideration of the following specification taken in conjunction with the accompanying drawings of which there are four (4) sheets and in which:

Fig. 1 represents a cutaway perspective view of the furnace embodying my invention, some of the parts of which having been omitted for the sake of clarity in the drawings;

Fig. 2 represents a vertical section taken along the line 2—2 of Fig. 1 and looking in the direction of the arrows;

Fig. 3 represents a partially broken away section taken generally along the line 3—3 of Fig. 1;

Fig. 4 is a perspective view of a partially assembled furnace embodying my invention;

Fig. 5 represents a section taken along the line 5—5 of Fig. 3 and showing the type of joint used to connect the two sections of my furnace;

Fig. 6 represents a perspective view, partially broken away, of the heat exchange surfaces and combustion chamber used in my furnace; and

Fig. 7 shows a circuit diagram of the wiring connection used in operating my furnace.

Manufacturers have tried for some time to develop a furnace of relatively large heating capacity which may be more or less completely assembled at the plant under expert supervision and sent out into the field and installed in the

user's home with very little labor on the part of the installing agent. This not only reduces the amount of tools and parts which the agent must keep on hand, but also provides for more perfect inspection of the assembly and insures better operation of the furnace after it has been installed. To this end, I have designed a furnace which may be divided generally into three sections. Each section may be individually assembled under expert direction at the factory and shipped to the agent to be installed in the user's home.

As is illustrated in Fig. 1, my furnace consists generally of an outer casing 10 having a return air opening 12, a heated air discharge or plenum chamber 14, and enclosed within the casing a combustion chamber 16, a radiator 18 surrounding the combustion chamber, a circulating blower 20, a draft inducing blower 22, fuel pump and motor assembly 24, filters 26 and various duct forming partitions which will be more particularly described later. Access to the interior of the furnace is obtained through a door 28 in the front of the casing.

As illustrated in Figs. 2, 3 and 4, the casing of my furnace consists of panels which may be made up as single stampings or sections having flanges 30 for bolting the various sections together. I have shown the sections of the casing to be made as two parts 32 and 34 each of which includes a side, half of the back and portions of the top and front of the casing. Each section is further divided along a horizontal plane approximately in the middle of the furnace as is indicated at 36. The interior of the casing is divided into three sections from the front to the rear by the partition 38 which defines a machine compartment between itself and the front wall of the casing, and the partition 40 which defines a plenum chamber between itself and the partition 38, and defines a combustion and heating compartment between itself and the rear wall of the casing. The partitions 38 and 40 are cut near their midsections along a vertical line and each half is joined to its respective half of the outer casing. The sections of the partitions are then joined by means of the joint illustrated in Fig. 5 which consists of a return flange 42 on each part of the partition 40 and a drive cleat 44 adapted to be driven over each of the return flanges. 41 indicates a clean-out port and 43 indicates a port for installing a thermostatic limit switch.

The casing is further divided from the top to the bottom by an arcuate panel 46 which de-

fines, between itself and the top of the casing, an air intake and filter chamber. The panel 46 is attached, as by welding, to one side of the casing at 48 and curved upwardly over and down the opposite side of the casing at 50 to form a duct between itself and the casing leading to the air circulating blower 20. The panel extends from the rear wall of the casing to the partition 40. As in the case of the partition panels 38 and 40, the panel 46 is divided near its mid-section so that each half may be assembled with its respective part of the casing proper. The two sections of this air duct partition may be fastened to the rear wall of the casing and to the partition 40 by means of a flange 52 along its edges welded to the connecting part.

Near the lower portion of the casing proper, I have provided a horizontal partition panel 56 which forms in conjunction with the air duct partition 46 and the vertical partition 40, a heat exchange chamber adapted to enclose the combustion chamber 16 and radiator 18. The panel 56 has an opening 58 for receiving the discharge from the circulating blower 20. As in the case of the other partition panels, the panel 56 is divided into two sections for assembly with each section of the outer casing.

The forward partition 38 does not extend as far down the casing as does the partition 40 and the lower end of the space between the partitions is closed off from the machine space within the casing by means of a horizontal panel 60 which is also divided along the middle portion. The panel 60 may be formed by bending over the bottom portion of the panel 38. When the panel 60 is sealed to the partition 40, it forms, in conjunction with that panel and partition 38, a plenum chamber extending upwardly to the opening 14 which is then attached to the heat distributing system in the house.

The partition panel 40 has a circular opening 62 cut near its midsection which is of such a size as to register with a flange on the radiator which will be described later. The partition 38 has a somewhat smaller circular opening 64 which is concentric with the opening 62 and arranged to register with the end of the combustion chamber as will be described later. The lower portion of the partition 40 has a small circular opening 66 cut in it immediately below the opening 62. This opening 66 is arranged to register with the exhaust connection from the radiator as will be more particularly described later. The middle of the panel 40 may be supported from below by a panel 68 which fits around the opening 66 and extends to the floor underneath the casing. The panel 68 serves to reinforce the various partitions where they are fastened in the center of the casing since these partitions support the combustion chamber and radiator.

The heat exchange surfaces, or radiator, and combustion chamber are more clearly illustrated in Fig. 6 and consist of a circular drum 70 forming the combustion chamber and having a flange 72 on its forward end. The rear end of the cylinder 70 is closed by a panel 74. Around the cylinder 70 is arranged an inner cylinder 76 and an outer cylinder 78 which are connected and closed at each end by rings or plates 80 and 82. It should be noted that the inner cylinder 76 is slightly longer than the outer cylinder 78, thus forming a flange 84 at the forward end of the radiator. The two cylinders 76 and 78 thus form an annular passage which is divided into a

spiral passage by means of a spiral fin 86. This fin 86 is formed of two angle members 88 and 90, one of which is welded to the outer cylinder and one of which is welded to the inner cylinder in confronting relationship with the first angular member. This spiral work construction is more particularly described and claimed in my U. S. Letters Patent for "Air conditioning apparatus," No. 2,172,399, dated September 12, 1939.

The combustion cylinder 70 has an opening 92 at the top and towards the rear end of the cylinder. This opening 92 is connected by means of a short section of pipe 94 with a corresponding opening 96 in the inner cylinder 76 of the radiator. This passage allows the hot gases from the combustion chamber to escape to the spiral passage of the radiator. The pipe 94 also serves to support the radiator with respect to the rear end of the combustion chamber cylinder. The forward end of the radiator is held in position relative to the combustion chamber by means of the struts 85.

The forward end of the combustion chamber cylinder may be lined with a heat resisting material, such as fire brick, to prevent the burning of the metal at a point adjacent the end where the flame is propagated. I have shown this fire brick to consist of a circular lining 98, an end disc 100 with a hole 102 in the center thereof, and a baffle 104 toward the rear end of the flame retaining section of the combustion chamber.

It is to be noted that the combustion chamber cylinder 70 is considerably smaller than the inner cylinder 76 of the radiator, thus, there is provided an annular space between the radiator and the combustion chamber through which air is adapted to pass into the plenum chamber. The flange 84, on the radiator registers with the opening 62 in the partition panel 40 and may be fastened thereto as by bolting or welding. The opening 64 in the partition 38 registers with the flange 72 on the forward end of the combustion chamber, and these parts may be joined as by bolting or welding. The forward end of the combustion chamber and radiator assembly is thus supported upon the partition panels 38 and 40. The rear end of the combustion chamber may be further supported from the casing by means of a pipe 104 bolted or fastened to the rear end of the combustion chamber and passed through the casing as at 106. The circular plate 108 is positioned directly behind the combustion chamber to shield the outside wall of the casing from heat radiated from the combustion chamber. The plate may be held in spaced relation with the casing by means of a series of clips 110.

At the front of the radiator, and at the bottom thereof, I have provided an opening 112 to which is connected a short pipe section 114 which projects through the hole 66 in the partition 40 and forms an exhaust opening for the radiator.

After the fire brick 98, 100 and 104 has been inserted into the combustion chamber, the front plate 113 is then bolted over the front of the combustion chamber. Plate 113 has a thickened portion or boss formed in the center thereof as indicated at 115. This boss 115 forms a burner unit having an inwardly conical bore 116 and radially arranged holes 118 extending into a central bore 120 which communicates axially with the hole 102 in the insulating material or fire brick 100. A burner nozzle 122 is positioned within the conical opening 116 as are two ignition electrodes 124, for igniting the mixture of oil and air passing through the opening.

The air for heating the house is circulated through the house by means of the blower 20 which consists of a wheel or fan 130 positioned within a hood 132 having the intake opening 134 and a discharge opening 58 opening into the space around the radiator. The fan is provided with a pulley wheel 136 for rotating the fan wheel by means of a belt drive from the motor shaft. The hood 132 for the blower is arranged to rest on the floor inside the furnace and to support the partitions 40 and 56 for further supporting the combustion chamber and radiator assembly within the furnace.

The operating mechanism for the furnace consists of a motor 140 positioned on a solid base 142 together with an oil pump 144 which is coupled directly to the motor shaft 148 along with a pulley 148 which is adapted to drive the belt for driving the blower pulley 136. Also mounted on the base 142, at the opposite end thereof from the oil pump, is a second blower or suction pump 150 which is connected to the exhaust duct of the radiator by means of the vertical duct 152 and the horizontal pipes 154 and 156. The suction pump 150 contains a centrifugal blower wheel directly connected to the motor 140 by means of a shaft 153 and is arranged to conduct the products of combustion from the radiator and discharge the same through the pipe 158 to the chimney. The base 142 has attached thereto a crossbar member 160 for fastening the machine support to the blower 20 and to the supporting panel 68 thus insuring that the parts will be in proper alignment.

The controls and wiring for operating the furnace, as viewed in Fig. 2, consist of a terminal box 164, a thermostatic switch 166, provided with a heat responsive element 168 within the plenum chamber, a transformer 170 for supplying current to the ignition electrodes 124 and a proteco relay switch 172 having a thermostatic element 174 within the pipe 156 and subject to the temperature of the exhaust gases. A diagram of a possible wiring circuit is illustrated in Fig. 7 and operates as follows: Current is supplied to the terminal box 164 by means of the power circuit from the house 175. From the terminal box the circuit extends through the limit switch 166 to the transformer 170 which provides current to the electrodes 124. After passing the transformer 170, the current is supplied to the proteco relay switch 172 which is a manual control for turning the circuit on or off and also includes a delayed action circuit controlled by the thermostatic device 174. When the switch 172 is turned on, and after a definite time, if the temperature around the thermostatic device 174 has not risen to a predetermined figure due to the passage of burning gases therearound, the thermostatic switch 174 will reopen the motor circuit thus causing the flow of air and oil to the burner to cease. This is a safety feature in that a person can not turn on the furnace and go away and leave it running without flames starting. The furnace can not be filled with a dangerous mixture of oil and air which might later explode. The limit switch 166 operates to shut off the motor and furnace operation should the temperature in the chamber rise too high as would be the case if the fan belt driving the circulating fan 20 were to break. It should be obvious that the controls for the furnace may be rearranged to suit most any operating condition and may include a thermostat in the space being heated.

The conditioning of the air within the furnace is provided by means of the filters 26 which are supported in the top of the casing by means of angle members 27 fastened along the wall of the casing and along the partition 40 as well as across the center of the air intake chamber. The air may be humidified by means of a body of water positioned in the pan 180 at the bottom of the plenum chamber. The water supply may be kept at a constant level by means of a float valve 182 connected to the pan 180 by a pipe 181 and to which a supply from the water system of the house is connected. In case the filters 26 should become clogged, I have provided a by-pass damper 184 for the purpose of allowing air to escape past the clogged filters. In this manner there is no danger of there being a lack of air passing over the radiator and combustion chamber, and, thus, overheating is prevented. The damper 184 is so designed that on an increase in pressure the damper becomes unbalanced and swings to a permanently open position indicating that the filters are clogged and should be changed.

The passage through the furnace of air being heated is indicated by the full lined arrows and is as follows: Through the opening 12 in the top of the casing through the filters or through the by-pass damper down the side of the casing to the intake of the blower 20, then the air is forced upward inside of the partition 46 and around the outside of the radiator. After passing around the radiator, the air passes back and around the rear end of the radiator and into the annular passage between the radiator and the combustion chamber. The air is forced through this annular passage over the humidifying pan 180 and out through the plenum chamber past the limit switch control 168.

The path of the products of combustion is indicated by the broken line arrows and is as follows: The air is drawn in through the conical burner opening 116 and the radial openings 118 from the inside of the casing due to the suction created by the exhaust blower 22. In the burner head the air is mixed with oil from the nozzle 122 and is ignited by the spark from the igniters 124. The resulting flame is largely confined to the space within the combustion chamber which is lined with fire bricks. From there the hot gases pass into the rear end of the combustion chamber, out through the stack 94 in the top of the combustion chamber in the radiator between the two outer cylinders. In the radiator the gases spiral around and towards the front where they pass out the opening 112 through the pipe 156 past the thermostatic control 174 for the proteco relay, then through the pipe 154 to the duct 152 which forms the intake for the blower 22. After passing through the blower the products of combustion are blown out the pipe 158 and up the chimney.

It will be noted that with this arrangement I have provided that the flow of air being heated and the flow of the hot gases are reversed over the heating surfaces so that the difference in temperature of the two paths of gases is at a maximum at all time; thus, the air to be heated, which is coldest when it enters the furnace, is first brought in contact with the circular panel 46 which will be heated to some extent by radiation from the radiator. After the air has picked up some heat from this panel, it is brought into contact with the hotter surfaces of the radiator and, when the air has picked up heat from the

radiator and has risen to higher temperatures, it is conducted over the extremely hot surfaces of the combustion chamber within the radiator. Since the amount of heat which a fluid will pick up in passing over a heated surface depends upon the difference in temperature between the fluid and that surface, it is evident that I have provided for a maximum amount of heat transfer between the air being heated and the products of combustion.

Since the draft for drawing air into the combustion chamber and disposing of the products of combustion is maintained by the blower 150, the furnace may be operated with practically any type of chimney. Further, the furnace may be tested and the controls adjusted at the factory by experts without having to know the type and efficiency of the stack to which the furnace is to be attached. This insures efficient operation of the furnace regardless of the skill of the dealer who installs it.

While I have described my invention in some detail, I intend this description to be an example only and not limiting upon my invention which is defined in the following claims.

I claim:

1. In a warm air furnace adapted to be erected in a confined area, a substantially cylindrical combustion chamber, an annular elongated radiator, said radiator being disposed about the outer wall of said combustion chamber in spaced apart relationship thereto and forming with said combustion chamber a unit assembly, an outer furnace casing divided into two parts separable at a vertical plane substantially bisecting the casing longitudinally, and partial partition and supporting walls carried by each of said casing parts arranged so that the said walls of one said part cooperate with the said walls of the other said part to support said unit assembly substantially centrally within said casing and to provide air conducting passageways through the casing in immediate contact with the exposed walls of the combustion chamber and radiator of said unit assembly.

2. In a warm air furnace as defined in claim 1, the disposition of the said combustion chamber and radiator unit assembly being such that its central axis is in a horizontal plane extending longitudinally of said casing and vanes within said radiator directing the flow of hot gases and products of combustion in a helical path during its passage longitudinally through the radiator.

3. In a hot air heating assembly including a 55 housing having a cold air inlet and a hot air

outlet, means in said housing defining a path of flow for air from said inlet to said outlet comprising a generally centrally positioned elongated drum-like stove, a hollow wall tubular radiator embracing said stove in spaced generally concentric relation thereto forming an air heating space therebetween, oil burning means located in a first end portion of said stove, conduit means placing the other end of said stove in communication with the adjacent end of said hollow radiator, flue defining means communicating with said radiator adjacent said oil burning means for removing combustion gases, means including a blower for delivering substantially all of said cold air from said inlet first against the outside of said radiator, thence delivering all of said air around the end of said radiator remote from said oil burning means, then between said radiator and said stove, and conduit means adjacent said oil burning means for directing all of said hot air from between said radiator and said stove to said hot air outlet.

4. In a furnace including a surrounding housing provided with a cold air inlet and a hot air outlet, a stove and radiator arrangement within said housing defining an air heating space therebetween wherein the rate of heat transfer from said stove and radiator to said air is made to be substantially the same along the axial extent of said heating space, said arrangement comprising a central horizontally elongated drum-like stove, a hollow walled tubular radiator embracing said stove and spaced in generally concentric relation thereto, oil burning means located in one end of said drum-like stove, conduit means placing the other end of said stove in communication with the juxtaposed end of said hollow radiator, flue defining means communicating with said radiator at the other end thereof adjacent said oil burning means for removing combustion gases, means shutting off the entry of air between said radiator and said stove adjacent said oil burning means, the space between said stove and said radiators adjacent the other end thereof being open for the entry of air thereto, means including a blower for delivering cold air from said inlet first against the outside of said radiator thence around the open end of said radiator remote from said oil burning means and then between said radiator and said stove, and conduit means adjacent the other end of said space juxtaposed to said oil burning means for directing hot air from between said radiator and said stove to said hot air outlet.

MORITZ L. MUELLER.
